STAIR TREAD

Filed Nov. 17, 1928

UNITED STATES PATENT OFFICE

EDGAR L. LOUDENSLAGER, OF TOLEDO, OHIO, ASSIGNOR, BY MESNE ASSIGNMENTS, OF
ONE-HALF TO ARTHUR J. HOSLER, OF TOLEDO, OHIO

STAIR TREAD

Application filed November 17, 1928. Serial No. 320,201.

This invention relates to floor covering sections as complete units for major show and major wear portion ready variation and replenishment.

5 This invention has utility when incorporated in stair tread units for resultant tread framing base with the tread general wear face adapted for ready selective design, and such harmony as to color and character as 10 may be desired with ready facility for replacement as worn.

Referring to the drawings:

Fig. 1 is a fragmentary view in perspective of a portion of a flight of stairs having an 15 embodiment of the invention incorporated as treads therefor;

Fig. 2 is a plan view of a tread framing unit, portions of the filler and its anchor being broken away;

20 Fig. 3 is a section on the line III—III, Fig. 2; and

Fig. 4 is a section on the line IV—IV, Fig. 3.

Flight of stairs is shown as having risers 1 25 and tread bases 2. Disposed on these tread bases is a unit herein shown as of a flexible material such as rubber and molded to form, involving intermediate relatively thin diaphragm or cushion region 3 bounded by outwardly beveled rear frame side 4 and outwardly beveled frame sides 5, 6. These frame sides 5, 6, are connected by forward frame side 7 having downwardly-curved tread-base engaging gripping extension 8..

35 In practice, these tread frame units may be cemented or anchored along the frame side 4 by screws or tacks 9 driven into the tread base 2, thus effectively holding the unit against lateral shifting, while the extension 40 8, as hanging forward, may snugly fit over the overhang from the tread base 2. Upon this thin sheet or diaphragm 3 within the framing 4, 5, 6, 7, may be smeared an adhesive 10, preferably one which may maintain some 45 flexibility when dry, as a heavy body linoleum cement.

With this flexible adhesive 10 thus spread, 50 filler or tread proper 11 previously cut to just fit in the frame is placed in register in the frame. The trimming or cutting of this

filler 11 is such that it fills the full frame and may even project under the overhang portions of the frame 4, 5, 6, 7, to thereby provide flush joint 12 therewith. This filler 11 is preferably a material which is not rigid. 55 It may be a print or inlaid linoleum of a selected design to be in harmony with the wall decorations or stair way or other matters as to which harmony is desired. While such adaptations may be one followed for back stairs or apartments, for front stairs or hotels the filler 11 may be of warp and woof provided carpet with or without nap so that there may be harmonious selection even as to high grade rugs or other types of floor 60 coverings at either end of the flight of the stairs.

In practice, the treads of the stairs receive the greatest usage and are the major portions shown as in the region within the framing. 70 This region as thus subjected to the arduous wear may have the material selected to resist such wear. However, in the event there is a passing of the appearance as desired, due to the failure to resist the character of wear to 75 which it is subjected, the framing need not be discarded but the filler 11 may be removed therefrom for replacement or to be in harmony with such change sought in the refinishing of the treads.

80 In the initial manufacture, some pressure is applied to the filler to hold it in position until the cement has set therewith. Accordingly, if the replacement be made on the stairs without removing the framing, it is important to have the filler held in position against curling loose until the cement has set therefor.

85 With the framing in use on the flight in a home, cleaning of its upper surface may be 90 readily effected, while accumulation of material thereunder may be prevented by merely lifting the overhanging extension 8 and thus flexing the frame with its filler back to allow sweeping or other dusting thereunder.

95 What is claimed and it is desired to secure by United States Letters Patent is:

1. A cushion tread for supporting a floor covering comprising a thin resilient diaphragm base, said base having a thickened in- 100

tegral flexible periphery forming a marginal frame therefor said frame having its inner side tapering outwardly and downwardly toward the base from the inner edge thereof, and a filler section mounted on said base flush with and framed by said thickened periphery.

2. A cushion tread for a step comprising a thin resilient diaphragm base, said base having a thickened integral periphery forming a marginal frame therefor and flexible therewith, said frame having its inner side tapering outwardly and downwardly toward the base from the inner edge thereof, a filler section mounted on said base flush with and framed by said thickened periphery, and anchoring means for one edge of the tread leaving the base and frame with the filler therein free to swing clear of the step on which mounted with said anchored edge as a hinge.

3. A cushion tread for a step comprising a thin resilient diaphragm base, said base having a thickened integral periphery forming a marginal frame, means anchoring one edge of the tread to a step, said frame on the edge of the tread opposite the anchored edge comprising a downwardly-curved step-edge gripping extension, said base and frame being flexible throughout, and a filler section mounted on said base to have its edges abut the inner side of said frame.

In witness whereof I affix my signature.
EDGAR L. LOUDENSLAGER.
